UNITED STATES PATENT OFFICE.

PAUL F. WILLIAMS, OF CHICAGO, ILLINOIS, ASSIGNOR TO G. & W. ELECTRIC SPECIALTY CO., OF CHICAGO, ILLINOIS, A CORPORATION OF ILLINOIS.

PROTECTIVE DEVICE FOR USE IN CONNECTION WITH POTHHEADS AND SIMILAR STRUCTURES.

Application filed August 10, 1917. Serial No. 185,454.

To all whom it may concern:

Be it known that I, PAUL F. WILLIAMS, a citizen of the United States, residing at Chicago, in the county of Cook and State 5 of Illinois, have invented a certain new and useful Improvement in Protective Devices for Use in Connection with Pothheads and Similar Structures, of which the following is a full, clear, concise, and exact description, reference being had to the accompanying drawings, forming a part of this specification.

My invention relates to pothead structures or similar devices.

15 One of the objects of the invention is to provide a device for use in connection with a pothead or similar structure by which the pothead may be protected from the weather or elements when it is opened up by a work- 20 man so as to disconnect a line or otherwise. Another object of the invention is to pro- 25 vide a device by which a workman operating upon a pothead to disconnect the line or otherwise, may be protected against pos- 30 sible injury from a live conductor.

Another object of the invention is to pro- 35 vide substantially a single device which shall afford both of the protections before specified.

40 A further object of the invention is to provide for the convenient arrangement of said protective device in connection with a pothead or similar device with which it is to be used.

45 Other objects of the invention will appear hereinafter.

In the accompanying drawing Fig. 1 is a front elevation of a pothead device such for example as shown in my Patent No. 40 831,815, September 25, 1906, and a protective device for use in connection therewith embodying my present invention, said latter device being shown in vertical section;

Fig. 2 is a similar view showing the pot- 45 head and protective device arranged for protective use;

Figs. 3 and 4 are horizontal sections taken on lines 3-3 and 4-4, respectively in Fig. 1.

50 Referring to the drawings and especially at first to Fig. 1, I show a horizontal mem- ber 1, which is understood to be a cross arm of a pole such as ordinarily used in electric lighting systems. Upon this cross arm 1

I show a pothead 2 mounted by means of 55 bolts 3-3 passing through the cross arm 1. The pothead 2 is similar to the one shown in my aforesaid Patent No. 831,815, al- though of course my present invention is not to be understood as being limited for 60 use only in connection with such potheads. Said pothead 2 has a base 2^a and a top or cover 2^b in accordance with the well known construction of said device. A cable 4 enters the lower end of the base member 2^a 65 and an overhead conductor 5 enters the upper end of the top or cover 2^b. Said base and top members are provided with co-op- 70 erating metallic contact members 6 and 7 by which connection may be made between the conductor 5 and cable 4 and also by which such connection may be broken by removing the top 2^b from the base 2^a, thereby open- 75 ing the line for various purposes, as well known in the art.

In the use of such a pothead device it will be seen that when the top 2^b is removed from the base 2^a, the latter will have its upper end open and exposed to the weather, so that in case of rain, snow, sleet or the like, moisture may get to the interior of the pothead and thereby permit damage from short circuiting or otherwise. It will also be seen that the lower end of the metallic contact member 6 projects beyond the bot- 80 tom of the cover 2^b and inasmuch as this cover 2^b is free to swing about in the air when moved from the base 2^a, said contact member 6 may inadvertently strike against the person of a workman manipulating the 85 device and in case the overhead conductor 5 is alive, might do such workman a very substantial injury. In my present invention I provide two devices, one for protect- 90 ing the base of the pothead from the weath- 95 er when the top is removed, and the other for preventing a workman from being in- jured by the exposed metallic part in the head 2^b such as the contact member 6. These two protecting devices or elements, I pref- 100 erably combine into a single device, there- by effecting cheapness, simplicity, compact- ness and so on.

In the drawing, still referring to Fig. 1, I show such a combined device consisting 105 of a base portion 9 and a top or cover mem- ber 10, combined and arranged together and adapted to be mounted upon the cross arm

1 adjacent to the pothead 2. The base member 9 is preferably in the form of a vertically disposed tubular member open at the top and provided with a flat portion 11 at the bottom, through which portion 11 bolts 12 may be passed to attach the device to the cross arm 1. The interior bore or chamber 14 is of ample size to accommodate the projecting end of the contact member so that the top 2^b of the pothead when removed from the pothead 2 may be set upon the upper end of the member 9 and will be supported by the latter, the contact member 6 projecting down into the bore 14, as shown in Fig. 2. The top or cap 10 is of such size and shape as to fit over the upper end of the base 2^a of the pothead when the cap 2^b is removed, said cap 10 being shown in such position in Fig. 2. In other words when the pothead is disconnected by the removal of the cap 2^b, said cap 2^b may be placed upon the top of the base member 9 on the protective device and the cap 10 of the protective device may be in turn placed upon the top of the pothead base 2^a. In this way the pothead top 2^b is supported in a fixed position so that it will not swing about in the air in an objectionable manner and its projecting contact member 6 will be covered so as to prevent said contact member from coming into contact with the person of a workman or with any other object. At the same time the cap 10 protects the upper end of the pothead base 2, and thereby sufficiently shields and protects the interior of the pothead from the weather. Thus both

the workman and the pothead and electrical apparatus connected therewith are adequately protected by a simple and inexpensive device which can be easily and cheaply constructed and mounted in a small space and compact manner in close association with the pothead itself. These protective devices may be made of any suitable insulating material, but I prefer to make both the base 9 and cover 10 of porcelain as the same can be readily formed and will give satisfactory results.

I prefer to use the two parts of the device, namely the base 9 and the cover 10 and unite them to form a single device as shown herein, although it is obvious that either one of said parts could be used by itself and mounted separately or in some other different manner.

It will be understood that changes and modifications may be made without departing from the spirit of the invention.

What I claim is:

The combination with a pothead device consisting of a body and a cap to be mounted thereon, a dummy device provided with a cap adapted to fit upon the upper end of the pothead body when the pothead cap is removed, and a body on which said pothead cap may be mounted, and means for mounting said pothead and dummy devices near one another.

In witness whereof, I hereunto subscribe my name this 26th day of July A. D., 1917.

PAUL F. WILLIAMS.
